ORGAN CONSOLE

George H. Stephens, Glencoe, Ill., assignor to Hammond Instrument Company, Chicago, Ill., a corporation of Delaware

Application June 23, 1950, Serial No. 10,715

Term of patent 14 years

(Cl. D56—2)

To all whom it may concern:

Be it known that I, George H. Stephens, a citizen of the United States, residing at Glencoe, State of Illinois, have invented a new, original, and ornamental Design for Organ Console, of which the following is a specification, reference being had to the accompanying drawing, forming a part hereof.

The single figure of the drawing is a perspective view of an organ console showing my new design.

I claim:

The ornamental design for an organ console, as shown.

GEORGE H. STEPHENS.
